Atty.

UNITED STATES PATENT OFFICE

LEWIS P. WOODS, OF INDIANA, PENNSYLVANIA.

IMPROVEMENT IN MACHINES FOR STUFFING HORSE-COLLARS.

Specification forming part of Letters Patent No. 123,139, dated January 30, 1872.

SPECIFICATION.

To all whom it may concern:

Be it known that I, L. P. Woods, of Indiana, in the county of Indiana and State of Pennsylvania, have invented a new and useful Machine for Stuffing Harness-Collars and other like purposes; and I hereby declare that the following is a full, clear, and exact description of the construction and operation of the same, reference being had to the annexed drawing making a part of this specification, in which—

Figure 1 is a plan or top view of the machine. Fig. 2 is a perspective of the same. Fig. 3 is a vertical section of the box. Fig. 4 is an end view of the machine, and Fig. 5 is a section of the stand for securing the collar; reference being also had to the letters and figures of reference marked thereon.

To enable others skilled in the art to make and use my invention, I will proceed to describe its construction and operation, viz.:

I construct, of wood, a frame of any desirable size, consisting of four posts mortised into and secured at the top and bottom and set up at any desirable angle, the upper or top rails being secured by a cross-piece secured to the front end of the same by a cross-piece extending any desirable distance beyond the same. Upon each of the top rails I secure, in a firm manner, plates of iron or other metal, each slightly projecting over the inner edge of the rails, and forming a guide-way, and, as additional strength at the rear end of the frame, I affix a bar of any desirable size, each end of which is firmly secured to the top rails, as is shown at A. I then construct a feed-box, of any desirable size and material, which is firmly affixed to the cross-rail above mentioned, as is shown at B, the inside of which is open at the top, as is shown at C, and is constructed of three horizontal divisions, $a a' a''$, the two inner partitions or dividing sides being only attached to the inside of the ends of the box by two or more spiral springs, so that the middle division of the box, in which is to be placed the straw, cotton, or other material to be used for stuffing, can be filled as desired; and as the said material is used the dividing sides, by the action of the springs, press the feeding material together, so as to be readily taken up by the plunger c , hereinafter mentioned. By means

of leather straps $d d'$, passing from each of the dividing sides to which it is affixed through the end of the box, the dividing sides can be adjusted by pins passing through such leather strap on the outside of the box at any desirable part to admit the feeding material into the middle division of the box, as is shown at D. Above the cross-bar of the frame is an opening in the middle division of the box, of any desirable size, with a corresponding opening through the front side of the box, as is shown at E. Through these openings a plunger, c , constructed of iron or other metal, of any desirable size, is made to pass forward and back through the same by means of a lever, F, and cross-head F' , the guides $e e'$ above mentioned, or by any other mode by which it may be desirable to force the plunger C through the middle division of the feed-box and withdraw the same. The front end or point of the plunger is made flat, with a semicircular indentation or cavity, c' , or with points, so as to readily force the feed from the box and not pull the same back into the box. Working between the frame and box is a slide, f , Fig. 2, attached to the frame by a spring, as is shown at G, through which slide the plunger passes; and by means of a treadle, g , secured to the frame, as shown at H, the slide will press upon the plunger and thus regulate the action of the plunger; and by means of the spring the slide is kept clear the plunger when the treadle is not used. Upon the front side of the box, over the opening above mentioned, is secured a nose-piece, as shown at I, composed of iron or other material, through which the plunger passes. This nose-piece has a rim of suitable size on the outward end, and over which the opening of the collar or other article which it is designed to stuff or fill is placed and firmly secured by means of clamps, as is shown at K. I then construct, of wood or other material, a frame of proper size with a plank top, with a groove cut in the plank, as shown at L, of any suitable width, but extending the width of the plank. Over the edges of the groove, so as to enable a slide to work, I affix a slide or guide-way. I then construct a slide, of iron or other material, grooved so as to work on the said slide. In the center of the slide is a slot to permit a screw-bolt to pass through and play

in such slot, so as to be secured at any point of the same. Above this is a circular or other desirable shaped piece of wood, upon which, and firmly affixed to it, is the mold or piece, of wood or metal, so arranged as to receive around it a portion of the collar which it is intended to fill, the end of which is fastened in the manner above mentioned over the rim of the nose-piece affixed to the box; and, by changing the mold used as may be desired, the machine will stuff and, by the mold, shape the article. A bolt-screw with its head catching below the slide and passing through the mold and the support for the same, and fastened by a nut on

the top of the mold, will permit the mold to be placed at any desirable position while filling the collar or other article.

Having thus described my invention, what I claim as my invention, and desire to secure by Letters Patent, is—

The combination of the feeding-box B, plunger c, and the mold-stand with the treadle and slide, constructed, arranged, and operating substantially as herein described.

L. P. WOODS.
